DESIGN FOR A PLATE WHIRLER

Glenn W. Tamm, Chicago, Ill., assignor to
American Type Founders, Inc., Elizabeth, N. J.,
a corporation of New Jersey

Application July 20, 1939, Serial No. 86,109

Term of patent 7 years

To all whom it may concern:

Be it known that I, Glenn W. Tamm, a citizen of the United States, residing at Chicago, county of Cook, and State of Illinois, have invented a new, original, and ornamental Design for a Plate Whirler, of which the following is a specification, reference being had to the accompanying drawing, forming part thereof.

Figure 1 is a perspective view of a plate whirler showing my design.

Figure 2 is a perspective view taken from the side opposite to that shown in Figure 1.

The opposite end is similar to that shown in Figure 1.

I claim:

The ornamental design for a plate whirler, as shown and described.

GLENN W. TAMMEN.
